RAIL LUBRICATING APPARATUS

Charles Stern, Jersey City, N. J.

Application July 8, 1936, Serial No. 89,499

16 Claims. (Cl. 184—3)

This invention relates to rail lubricating apparatus.

An object of this invention is to provide apparatus of the character described, operated by the wave of a rail when a train passes thereover, for depositing lubricant on the head of a rail, the construction being such that the apparatus will operate to discharge lubricant even with relatively small movements of the rail, while permitting adjustment of the amount of lubricant discharged.

A further object of this invention is to provide in apparatus of the character described, highly improved means for depositing lubricant on the rail head and wheel flanges, constructed so as not to be subject to pounding from the flanges of the wheels passing over the rail, whereby to insure long life without material wear.

20 A still further object of this invention is to provide apparatus of the character described adapted to be arranged in various positions with respect to the rails and in which the operating mechanism for forcing the grease from its reservoir, is not anchored to the rail while being actuated thereby, to facilitate installation.

Another object of this invention is to provide in apparatus of the character described, a lubricant tank of relatively large capacity, which may nevertheless be conveniently embedded in the roadbed between a pair of adjacent ties.

Still another object of this invention is to provide compact and durable rail lubricating apparatus of the character described, which shall be relatively inexpensive to manufacture, comprise few and simple parts, be positive in operation, easy to install and adjust, and withal, practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a top plan view of lubricating apparatus embodying the invention installed to lubricate a rail;

Fig. 2 is a cross-sectional view taken on line 2—2 of Fig. 1;

Fig. 3 is an enlarged cross-sectional view taken on line 3—3 of Fig. 2;

Fig. 4 is an enlarged cross-sectional view taken on line 4—4 of Fig. 2;

Fig. 5 is an enlarged cross-sectional view taken on line 5—5 of Fig. 1;

Fig. 6 is an enlarged cross-sectional view taken on line 6—6 of Fig. 5;

Fig. 7 is a cross-sectional view taken on line 7—7 of Fig. 5;

Fig. 8 is a top plan view of a lubricant discharge device, forming part of my invention, with parts broken away to show the interior construction;

Fig. 9 is a top plan view of one end of the clamp for mounting the discharge device;

Fig. 10 is a top plan view of a tank and operating device illustrating another form of the invention;

Fig. 11 is a side elevational view of the structure shown in Fig. 10;

Fig. 12 is a cross-sectional view taken on line 12—12 of Fig. 11;

Fig. 13 is a horizontal, cross-sectional view through the clutch and clutch operating mechanism shown in Fig. 11; and

Fig. 14 is a cross-sectional view taken on line 14—14 of Fig. 11; and

Fig. 15 is a partial cross-sectional view of the upper end of the discharge device in an adjusted position with respect to the head of the rail.

Referring now in detail to the drawings, 10 and 10a designate a pair of parallel rails mounted on parallel transverse ties 11. In accordance with the invention, there is provided apparatus for lubricating the inner surface of the head of the rail 10a. The apparatus comprises generally of a tank 13 embedded within the roadbed adjacent the rail 10 and connected by conduit 14 to a discharge device 15 mounted on a clamp 16 fixed to said rail 10a. The apparatus furthermore comprises operating mechanism 19 actuated by the wave of rail 10 when a train passes over the rails for forcing lubricant within the tank through the conduit 14 to said discharge device 15, whereby to deposit lubricant on the head of said rail 10a, as will be explained in detail hereinafter.

The tank 13 comprises a bottom plate 20 formed with a circular raised portion 21 and an outwardly extending peripheral flange 22. The plate 20 is formed with a central screw-threaded opening 23; and also with a passage 24 connecting an upper surface of the raised portion 21 with an outer edge of the flange 22. Mounted on the plate 20, is a cylindrical member 25, the lower end

whereof snugly receives the raised portion 21 of the plate and contacts flange 22.

Mounted on top of the cylindrical member 25, is a tank head or member 26, preferably in the form of a casting and having an annular horizontal flange or wall portion 27 aligned with the flange 22 and formed with a circular groove 28 on the undersurface thereof receiving the upper edge of the cylinder 25. The flanges 22 and 27 are formed with aligned pairs of openings receiving connecting bolts 29 which serve to clamp the head 26 and the plate 28 against opposite sides of the cylinder 25. Extending from the horizontal flange or portion 27 of said member 26, are upstanding parallel side walls 30, disposed parallel to and preferably between the ties 11; an upstanding end wall 31 parallel to the rails, and an upwardly and outwardly inclined end wall 32 opposite to the wall 31. The walls 30, 31 and 32 are all interconnected by a top wall 33 parallel to the flange or portion 27.

The end wall 31 is formed with a screw-threaded opening 35, to which there is screwed one end of the conduit 14. The top wall 33 is formed with a central boss 36, having a through opening 37 aligned with the threaded opening 23 in the bottom plate 20. The top wall 33 is furthermore formed with an opening 40 for a screw plug 41. When the plug is removed, a stick may be inserted to determine the amount of lubricant in the tank. Said top wall 33 is furthermore formed with a downwardly extending boss 42, having a through opening 42a, for the purpose hereinafter appearing. Adjacent the inclined wall 32, the top wall 33 is formed with an oblong opening 43 to receive a clamping closure 44 which may be opened for the purpose of inserting lubricant into the tank. The head 26 has a horizontal bracket extension 46 at substantially the level of top wall 33, projecting from wall 31 beneath the adjacent rail 10.

Screwed within opening 23 of bottom plate 20, is a screw 50 projecting somewhat above the plate and being formed with a depression or 45 socket at its upper surface. Journalled within the through opening 37 of the boss 36, is an axial member 51 provided with a collar 52 contacting the underedge of the boss. The portion 53 of the member 51 above the collar 52 is smooth, 50 whereas the portion 54 below said collar is screw-threaded. The lower end of the member 51 is formed with a socket; and a metal ball 55 is interposed between the lower end of the member 51 and the upper end of the member 50, said 55 ball being received within the opposed sockets of said members. A packing gland may be screwed within the boss 52.

Disposed within the tank is a piston 56 comprising a plate 57 formed with a central threaded opening engaging the threaded portion 54 of the member 51. Bolted to the underside of the member 57 is a plate 58 clamping thereto an annular wiper 60 engaging the inner surface of the cylindrical wall 25. A vertical guide rod 61 parallel to the axial member 51 may extend through the tank, passing through registering opening in the plates 57, 58 and being fixed at the ends thereof to the head 26 and plate 20. It will now be understood that as the member 51 is rotated (in the manner to be explained hereinafter) the piston 56 will move up or down depending upon the direction of rotation, the guide rod 61 preventing the piston from rotating.

The operating mechanism 19 for forcing grease 75 within the tank and above the piston through

the conduit 14, comprises a bearing 64 mounted on the bracket extension 46 and rotatably supporting a horizontal shaft 65 disposed at right angles to the rail 10. Attached to one end of the shaft 65, as by a universal joint 66, is a shaft 67. 5 Pivoted about a vertical axis to the top wall 33 of the tank, as at 68 directly below the universal joint 66, is a bracket 69 provided with a pair of spaced bearings 70, in which the shaft 67 is rotatably supported. On said shaft 67 and between 10 the bearings 70, is a worm 71 meshing with a worm wheel 72 fixed on the upper end of the member 51.

Means is provided for releasably retaining the worm 71 in mesh with the worm wheel 72. To 15 this end, there is slidably mounted within the opening 42a of boss 42, a pin 74 having a collar 75 at the lower end thereof. Interposed between the collar 75 and the boss 42, is a coil compression spring 77. At the upper end thereof, pin 74 is provided with a head 78 and a handle 79. The head 78 is normally in engagement with the outer end of the bracket 69 for retaining the worm 71 in engagement with the worm wheel 72. When the piston 56 moves toward the top, the same will engage the lower end of the pin 74 to lift the latter against the pressure of the spring 77 to raise the head 78 above the lower end of the bracket 69, thus permitting said bracket to swing about the pivot 68 30 to the dotted line position shown in Fig. 1, the worm 71 thus becoming disengaged from the worm wheel 72. To swing the bracket to the dotted line position in Fig. 1 upon release thereof, there is provided on the top wall 33 a stop 35 80, a compression spring 81 being interposed between said stop and the bracket and pressing against said bracket.

On the shaft 65 is a clutch 85 adapted to be rotated by the wave motion of the rail 10, 40 to intermittently rotate the shaft 65 when trains pass over the rail. The clutch 85 comprises a sleeve 86 fixed on the end of the shaft 65. The sleeve 86 is formed with a plurality of curved teeth 87. Rotatably mounted on said shaft 65 45 and between the sleeve 86 and the bearing 64, is a member 88 having an annular flange 89 surrounding the teeth 87. An annular liner 90 of hardened metal may be fixed to the inner surface of the flange 89. Between the liner 90 50 and the teeth, are rollers 91 disposed in the notches or spaces formed between the teeth and said liner. Springs 92 within sockets formed at the ends of the teeth 87 serve to press the rollers away from the ends of the teeth toward 55 the shallow portions of the notches. A cover 94 frictionally fitted on the flange 89 has an end wall 95 covering the notches and retaining the rollers therein.

Integrally formed with the member 88, is an 60 arm 97 on the upper end of which is a roller 98 engaging the undersurface of the adjacent rail 10. A spring 100 fixed to the member 88 at one end and to the bracket 46 at the opposite end, serves to maintain the roller 98 in 65 constant engagement with the rail.

It will now be understood that when the rail is depressed the member 88 will be rotated about the shaft 65, causing the rollers 91 to grip the teeth 87 and rotate the shaft 65. When the 70 rail moves up, the spring 100 will rotate the member 88 in an opposite direction without causing rotation of the sleeve 86 or shaft 65. The shaft 65 will thus be intermittently rotated when a train passes over the rail. Rotation of the 75

shaft 65 will cause intermittent rotation of the screw 51 in a direction for moving the piston upwardly to press the lubricant in the tank and above said piston, through the conduit 14 to the discharge member 15.

There is further mounted on the bracket 46, a friction brake 46a, having semi-cylindrical portions engaging the sleeve 86 and preventing retrograde movement of said sleeve.

10 A vent pipe 24a may be attached to the base plate 20 for communication with the interior of the tank through the passage 24, said pipe extending above the tank as shown in Fig. 2 of the drawings. The tank may be supported 15 on horizontal boards 20a and by vertical board 20b, engaging at its lower end one of the boards 20a and at its upper end the bracket extension 46. It will be noted that the distance between the walls 30 of the tank head 26 is less than 20 the diameter of the tank. Thus, should it be required to embed the tank between rail ties which are relatively close together, the tank body may be disposed beneath the ties and the tank head disposed between the ties. Thus, if the 25 diameter of the tank body is greater than the distance between a pair of ties, the body may be located below the level of the ties with the head projecting between the ties.

The lubricant discharge device 15 is mounted 30 on the clamp 16, as shown in Fig. 2 of the drawings. Said clamp comprises a pair of symmetrically disposed members 105 and 106, engaging opposite edges of the base of the rail. The member 106 comprises an elongated folded-over

35 channel-shaped portion 107, receiving one edge of the rail base and provided with a central depending apertured ear 108. The member 105 likewise comprises an elongated channel-shaped portion 109 receiving the other edge of the rail

40 base and provided with a depending apertured ear 110 aligned with the ear 108. A bolt 111 passing through the ears 108, 110 serves to fix the members 105, 106 to the rail. Portion 109 of clamp member 105 is provided with a pair

45 of spaced, horizontal, threaded openings 112 receiving therethrough, screws 113, the inner ends whereof are adapted to engage the outer end edge of the base of the rail, as shown in Fig. 6 of the drawings. Said portion 109 is also formed

50 with a pair of spaced vertical screw-threaded openings, into which are screwed vertical screws 114, each provided with a pair of spaced lock-nuts 115. Mounted on the screws 114 and supported by the nuts 115, is the discharge device 15.

55 Said device comprises a member 116 preferably in the form of a casting having horizontal end extensions 117 provided with slots 117a perpendicular to the rail, receiving therethrough the screws 114. The lock-nuts 115 are disposed

60 on opposite sides of extensions 117. The height of the discharge member may be regulated by suitably manipulating said lock-nuts 115. The member 116 has a flat upper surface 119 and is formed with a pair of parallel elongated chambers 120, 121 both open at the top. Said chambers may be interconnected by spaced trans-

65 verse openings 122. The member 116 is furthermore formed with a central nipple 123 communicating with the middle of the chamber 120. The nipple 123 is curved downwardly and is attached to one end of the conduit 14. Said member 116 is furthermore formed with a plurality of vertical through openings 125 for the purpose hereinafter appearing.

70 On top of the member 116 and contacting the

surface 119 thereof, is a washer or gasket 126, having a slot 127 registering with the chamber 121. On the gasket 126 are a pair of thin angular symmetrically disposed plates 129 and 130, preferably made of thin sheet metal, such as sheet steel. Each has a horizontal wall and a vertical wall. The vertical walls are close together forming therebetween a thin narrow slot 131a disposed directly above and registering with the chamber 121. A pair of thin metal plates 131b are interposed between the vertical portions of the members 129, 130, adjacent the ends thereof and forming end walls for the slot 131a. Said plates are welded or riveted to said vertical walls. On the horizontal portions of the members 129, 130, is a plate 131 formed with a slot through which the vertical portions of said members pass. The plate 131 is bolted to the member 116 by bolts 132 passing through the bolt openings 125.

20 It will now be understood that lubricant passing through the conduit 14 will enter the chamber 128, pass through the openings 122 to the chamber 121 and will then be forced upwardly through the slot 131a onto the side surface of the head of the rail. The discharge member 15 may be so adjusted in height as to bring the upper edge of the members 129, 130 substantially at the lower edge of the head of the rail. The discharge device 15 furthermore may be adjusted toward the rail by loosening lock-nuts 115. The lubricant, preferably a heavy graphite grease, passing through the slot 131a will be discharged in a thin sheet which will coil as it is deposited on the head of the rail. As the train passes over the rails, causing waving of the rail, the lubricant is discharged onto the side wall of the rail head and is taken up by the flanges of the wheels passing over the rail.

30 The discharge end of member 15 is so thin that the flanges of wheels passing over the rail will 40 not strike or pound or contact the same, thus insuring long life without material wear. The flanges of the wheels pick up the discharged lubricant without contacting the discharge device.

35 In Figs. 10, 11, 12, 13 and 14 there is disclosed another form of operating mechanism for forcing lubricant from a tank or reservoir through a conduit to the discharge device 15. As shown in said figures, there is provided a tank 13a substantially similar to the tank 13 shown in Fig. 2. 50 Mounted on the upper end of the axial screw 51a of said tank is a one-way clutch 85a similar to the clutch 85 shown in Fig. 3 of the drawings. The clutch 85a comprises a member 82a similar to the member 82 of Fig. 3, but having a horizontal pin extension 140, for the purpose hereinafter appearing. There is slidably mounted on the tank head 26a, a release pin 74a pressed downwardly by a compression spring, and formed at its upper end with a slot 141. A transverse pin 60 142 removably mounted at the upper end of member 74a crosses said slot. On said pin and within said slot, is a roller 142a. Adjacent the bottom of the slot 141 is another pin 143 carrying a roller 144.

65 For the purpose hereinafter appearing, the tank head 26a is provided with a pair of apertured ears 145 supporting a transverse pin 146. Pivoted on said pin, is a bell crank lever 147, having one arm 148 substantially in horizontal position 70 and projecting beneath the adjacent rail 10. Said arm 148 is formed with a slot 149 receiving therethrough a screw 150 fixed to said arm by a pair of lock-nuts 151. At the upper end of the screw is rotatably mounted a roller 152 engaging the 75

underside of the rail. The lever 147 furthermore comprises an upstanding arm 155 formed with a slot 156 at its upper end. Within said slot is a block 157 which may be fixed to the arm 155 in various adjusted positions along said arm, by a set screw 158. The block 157 is provided with a transverse pin 160 having projecting ends. At one end of a connecting member 161 is a bifurcated portion 162 receiving the upper end of the arm 157 and formed with apertures engaging the outer ends of said pin 160. The connecting member 161 is formed on the underedge thereof with a notch 165 engaging the pin 140 on the clutch 85a. Said member 161 furthermore passes through the slot 141 and between rollers 142a, 144. A coil tension spring 166 interconnects the arm 155 of the bell crank 147 with the tank head 26a.

It will now be understood that as the rail 10 moves up and down during passage of a train thereover, the bell crank 147 will be oscillated, in one direction by the rail and in the other direction by the spring 166. The spring 166 maintains roller 152 in contact with the underside of rail 10a. During oscillation of the bell crank, the connecting member 161 will be reciprocated to oscillate the member 88a of the clutch 85a. Such oscillation of the member 88a will intermittently rotate the screw 51a in one direction to raise the piston for forcing the lubricant through the conduit to the discharge device. When the piston strikes the underside of the pin 74a, said pin will be lifted for raising the connecting member 161 to disengage the pin 140 from the slot 165. A friction brake 170 may be mounted on the tank head and provided with semi-circular portions engaging opposite sides of the toothed portion 86a of the clutch. The screw 51a may be formed with a polygonal head 171 at its upper end to receive a wrench, whereby the screw may be rotated in a direction to lower the piston after the clutch has been disengaged, so that the tank may be refilled with grease. To permit such operation, the pin 142 is first removed and member 161 swung upwardly out of engagement with pin 140.

It will be noted that the stroke of the connecting rod 161 may be varied by adjusting the position of the screw 150 within the slot 149, and also by adjusting the position of the block 157 within the slot 156.

In Fig. 15, the discharge device 15 is shown in an adjusted position with the slot 131a substantially flush with the side of the rail and the vertical portion of the plate 130 substantially contacting said head and disposed therebeneath. With such arrangement, the discharge device may be placed at the curve of the rail where the flanges of the wheels press against the rail head due to centrifugal force, the lubricant being discharged into the space between the wheel flanges and the rail head, whereby the flanges wipe the lubricant against the rail head, the latter acting as a wiper without the discharge device being contacted by the flanges. A highly efficient lubrication of the rails and wheel flanges thus result.

If desired, the tanks and operating mechanisms of Figs. 2 and 11 may be installed in reverse positions at 180° from the positions shown in said figures, in which event the tanks will be located between the rails instead of outside of the rails.

It will now also be understood that the operating mechanisms illustrated in the drawings are not attached or anchored to the rail, the rollers

merely contacting the underside of the rail. Such construction simplifies installation and permits creeping of the rail without affecting the operating mechanism.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new my desire to secure by Letters Patent:

1. Rail lubricating apparatus comprising a vertical tank, an axial screw therein, a piston non-rotatably and slidably mounted in said tank, the upper end of said screw projecting above said tank, clutch means carried wholly by the projecting portion of said screw and means carried by said tank and controlled by the wave of a rail when a train passes thereover, for intermittently rotating said clutch means to intermittently rotate said screw to cause sliding movement of said piston, and means controlled by said piston to disconnect said clutch rotating means from said clutch means to render said clutch means inoperative.

2. Rail lubricating apparatus comprising a vertical lubricant tank adapted to be embedded within the roadbed adjacent a rail and having an axial vertical screw, a piston within the tank having a threaded connection to said screw, means to prevent rotation of said piston, a clutch on the upper end of said screw and above said tank, and a lever pivoted to said tank and engaging the rail and adapted to be moved by the wave of the rail when a train passes thereover and means operatively connecting said lever to said clutch for intermittently rotating said screw, said connecting means being disengageable from said clutch.

3. Rail lubricating apparatus comprising a vertical tank adapted to be embedded within the roadbed adjacent a rail and having a vertical axial screw, a piston within the tank having a threaded connection to said screw, means to prevent rotation of said piston within said tank, a clutch at the upper end of said screw and above said tank, a lever pivoted to said tank and having one arm engaging a rail, a connecting member interconnecting the other arm of said lever with said clutch, and a tension spring interconnecting an arm of said lever with said tank, said connecting member being disengageable from said clutch.

4. Rail lubricating apparatus comprising a vertical tank adapted to be embedded within the roadbed adjacent a rail and having a vertical axial screw, a piston within the tank having a threaded connection to said screw, means to prevent rotation of said piston within said tank, a clutch at the upper end of said screw, a lever pivoted to said tank and having one arm engaging a rail, a connecting member interconnecting the other arm of said lever with said clutch, a tension spring interconnecting an arm of said lever with said tank, and means controlled by said piston for disconnecting said connecting member from said clutch.

5. Rail lubricating apparatus comprising a lubricant tank adapted to be embedded within the

roadbed adjacent a rail, and having a vertical axial screw, a piston within the tank having a threaded connection to said screw, means to prevent rotation of said piston within said tank, a 5 one-way clutch operatively connected to said screw for intermittently rotating the latter, said clutch having an oscillating part, a lever pivoted to said tank, resilient means for retaining said level in engagement with the underside of said 10 rail, and a connecting member pivoted to said lever and releasably engaging said part of said clutch.

6. Rail lubricating apparatus comprising a tank, an axial, vertical screw-threaded member 15 within said tank, a piston within said tank having a threaded connection with said screw, means to prevent rotation of said piston within said tank, said screw having a portion projecting from said tank, a clutch on the projecting portion of said screw and having an oscillating part provided with a pin, and means pivoted to said tank and engaging a rail and a member pivoted to said means and having a notch to receive said pin.

25 7. Rail lubricating apparatus comprising a tank, an axial screw-threaded member within said tank, a piston within said tank having a threaded connection with said screw, means to prevent rotation of said piston within said tank, said screw having a portion projecting from said tank, a clutch on the extending portion of said screw and having an oscillating part, means engaging a rail operatively interconnected to the oscillating part of the clutch, a pin slidably mounted on said tank and adapted to be moved longitudinally by said piston, and means controlled by said pin for disconnecting said last means from said clutch.

8. Rail lubricating apparatus comprising a vertical tank adapted to be embedded within the roadbed adjacent a rail and having a vertical axial screw, a piston within said tank and having a threaded connection to said screw, means to prevent rotation of said piston within said tank, the upper end of said screw projecting above said tank, a clutch on said projecting portion of said screw, a lever pivoted to said tank, a member slidably mounted on an arm of said lever and having a roller engaging the underside of said rail, resilient means for maintaining said roller in engagement with said rail, said clutch having an oscillating portion provided with a projection, and a bar interconnecting said lever with said projection.

55 9. Rail lubricating apparatus comprising a vertical tank adapted to be embedded within the roadbed adjacent a rail and having a vertical axial screw, a piston within said tank and having a threaded connection to said screw, means to prevent rotation of said piston within said tank, the upper end of said screw projecting above said tank, a clutch on said projecting portion of said screw, a lever pivoted to said tank, a member slidably mounted on an arm of said lever and having a roller engaging the underside of said rail, resilient means for maintaining said roller in engagement with said rail, said clutch having an oscillating portion provided with a projection, a bar interconnecting said lever with said projection, a vertical member slidably mounted on said tank and adapted to be lifted by said piston and provided with a slot, and a pin at the upper end of said slot, said bar passing through said slot and adapted to be lifted out of engagement with said clutch part when said vertical member is raised by said piston.

10. Rail lubricating apparatus comprising a vertical tank adapted to be embedded within the roadbed adjacent a rail and having a vertical axial screw, a piston within said tank and having a threaded connection to said screw, means to prevent rotation of said piston within said tank, the upper end of said screw projecting above said tank, a clutch on said projecting portion of said screw, a lever pivoted to said tank, a member slidably mounted on an arm of said lever and having a roller engaging the underside of said rail, resilient means for maintaining said roller in engagement with said rail, said clutch having an oscillating portion provided with a projection, a bar inter-connecting said lever with said projection, a vertical member slidably mounted on said tank and adapted to be lifted by said piston and provided with a slot, and a pin at the upper end of said slot, said bar passing through said slot and adapted to be lifted out of engagement with said clutch part when said vertical member is raised by said piston, said pin being removable to permit said bar to be manually lifted out of engagement with respect to said projection.

11. In rail lubricating apparatus, a discharge device comprising a clamp fixed to the base of a rail, a pair of screws on said clamp, a member having openings receiving said screws and being fixed thereto by lock-nuts, said member having a pair of parallel chambers in the upper surface thereof and being formed with openings interconnecting said chambers, a nipple on said member communicating with one of said chambers, a gasket on top of said member having a slot registering with the other of said chambers, a pair of 30 symmetrically disposed members of angular transverse cross-section on said gasket having aligned portions contacting said gasket and parallel portions disposed parallel to one another and forming a slot therebetween registering with said other chamber, a pair of plates between said parallel portions to form ends for said slot, and a plate on said aligned portions having a slot through which said parallel portions pass, and means for fixing said last plate to said member.

40 12. A lubricant discharge device for a rail comprising a member formed with an elongated chamber open at the top, a pair of symmetrical members of angular transverse cross-section having coplanar portions and parallel portions, the 50 coplanar portions resting on said member and said parallel portions forming a narrow slot therebetween communicating with said chamber, means for closing the ends of said slot, and means for fixing said symmetrical members to said first member.

55 13. A lubricant discharge device comprising a clamp having a pair of parts engaging opposite edges of the base of the rail and formed with depending apertured ears, a bolt passing through the apertures in said ears for attaching said clamp parts together, one of said parts having a screw-threaded opening, a screw screwed within said opening and adapted to engage said rail, said part being formed with a pair of vertical screw-threaded openings, a pair of screws screwed within said pair of threaded openings, a member having apertured ears receiving said pair of screws and being fixed to said screws by lock-nuts, said member having a chamber, means for 60 feeding lubricant to said chamber, and means for carrying the lubricant within said chamber to the head of the rail.

65 14. A lubricant discharge device, comprising a member having a pair of parallel chambers in the 70

upper surface thereof and being formed with openings interconnecting said chambers, a nipple on said member communicating with one of said chambers, a gasket on top of said member having a slot registering with the other of said chambers, a pair of symmetrically disposed members of angular transverse cross-section on said gasket, having aligned portions contacting said gasket and parallel portions spaced from one another and forming a slot therebetween registering with said other chamber, means between said parallel portions closing the ends of said slot, a plate on said aligned portions having a slot through which said parallel portions pass, and means for fixing said last plate to said member.

15. A lubricant discharge device, comprising a clamp having a pair of parts engaging opposite edges of the base of the rail, means for attaching 20 said parts together, a pair of vertical screws on one of said parts, a member having a pair of parallel horizontal slots receiving said screws and being fixed thereto by lock-nuts, whereby said

member may be adjusted in height as well as toward and from the rail, said member being formed with a chamber, means for feeding lubricant to said chamber, and means for carrying the lubricant from said chamber to the head of the 5 rail.

16. Rail lubricating apparatus comprising a vertical tank adapted to be embedded within the roadbed adjacent the rail, a vertical axial screw within said tank, a piston within said tank having threaded engagement with said screw, means to prevent rotation of said piston within said tank, the upper end of said screw projecting above said tank, a clutch on said projecting portion of said screw, means pivoted to said tank 15 engaging said rail, resilient means for maintaining said pivoted means in engagement with said rail, said clutch having an oscillating portion, means interconnecting said oscillating portion with said pivoted member, and means controlled 20 by said piston to disconnect said pivoted means with said oscillating portion.
